DESIGN FOR A VENTILATOR

Jay P. Johnson, Euclid, Ohio, assignor to The Swartwout Company, Cleveland, Ohio, a corporation of Ohio

Application March 26, 1948, Serial No. 145,380

Term of patent 14 years

(Cl. D62—3)

To all whom it may concern:

Be it known that I, Jay P. Johnson, a citizen of the United States, residing at Euclid, in the county of Cuyahoga and State of Ohio, have invented a new, original, and ornamental Design for Ventilator, of which the following is a specification, reference being had to the accompanying drawing, forming a part thereof.

Figure 1 is a perspective view of a ventilator embodying my new design taken from below and forwardly of an upper front corner thereof;

Figure 2 is a perspective view taken from above and forwardly of a front corner oppositely of Figure 1, and

Figure 3 is a perspective view taken from above and behind a lower rear corner of the ventilator embodying my new design.

I claim:

The ornamental design for a ventilator, substantially as shown.

JAY P. JOHNSON.
